FLOOR LAMP

Charles W. Clemens, Nashville, Tenn., assignor to Aladdin Industries, Incorporated, Nashville, Tenn., a corporation of Illinois

Application February 8, 1954, Serial No. 28,902

Term of patent 7 years

(Cl. D48—20)

FIG. 1.

The dominant features of my design are shown in solid lines.

I claim:

The ornamental design for a floor lamp, substantially as shown and described.
